DESIGN FOR A BLANKET CLIP AND HOLDER

Seymour Tharler, Leominster, Mass., assignor to Zadek Feldstein Co., Inc., New York, N. Y., a corporation of New York

Application November 15, 1947, Serial No. 142,550

Term of patent 14 years

(Cl. D17—6)

To all whom it may concern:

Be it known that I, Seymour Tharler, a citizen of the United States, residing at Leominster, in the State of Massachusetts, have invented a new, original, and ornamental Design for Blanket Clip and Holder, of which the following is a specification, reference being had to the accompanying drawing, forming part thereof.

In the drawing:

Fig. 1 is a front elevational view of a blanket clip and holder, showing my new design;

Fig. 2 is an enlarged fragmentary top plan view thereof; and

Fig. 3 is an enlarged end view thereof.

I claim:

The ornamental design for a blanket clip and holder, as shown.

SEYMOUR THARLER.
